United States Patent Office.

JOHN HEGARTY, OF JERSEY CITY, NEW JERSEY.

Letters Patent No. 69,994, dated October 22, 1867; antedated October 17, 1867.

IMPROVEMENT IN PORTABLE FOUNTAINS.

The Schedule referred to in these Letters Patent and making part of the same.

TO ALL WHOM IT MAY CONCERN:

Be it known that I, JOHN HEGARTY, of Jersey City, Hudson county, New Jersey, have invented a new and improved Self-Acting Portable Fountain; and I do hereby declare that the following is a full, clear, and exact description thereof, which will enable others skilled in the art to make and use the same, reference being had to the accompanying drawings, forming a part of this specification, in which—

Figure 1 is a vertical sectional view of my improved fountain, and

Figure 2 is a plan or top view of the same.

Similar letters of reference indicate corresponding parts.

This invention relates to a fountain for propelling common or scented water, which can be placed in any room, and be removed with ease, and will be constantly working, only requiring the occasional winding up of a spring.

The invention consists in the use of a rotary or other pump, which is secured to the bottom of the basin, and which is operated by clock-work, so as to throw a jet of water through a pipe into an upper basin, from which the water returns to the main basin again.

The invention also consists in combining with this device a musical box, which is operated by the same clock-work that operates the pump, and a very agreeable and amusing ornament for parlors and drawing-rooms is thus constructed.

A represents a basin, supported by a pediment, B, that consists of any number of posts, which may be surrounded by ornamental basket-work or other suitable devices. The basin may be round or oval, and is made of cast iron or any other suitable material. To the bottom of the basin is secured a metal ring, C, which forms a cylinder, in which the piston D of the pump operates. The water in the basin A flows into the cylinder, and is thence forced by the piston D towards the bottom of the cylinder, and thence up through a pipe, E, that communicates with the lower end of the cylinder C, as shown. Through the tube E the water is propelled into an upper basin, F, supported on a suitable pediment, G, as shown. Holes $\alpha\alpha$ are arranged in the sides of the basin F, through which the water returns into the basin A in jets of suitable thickness, thereby adding to the pleasing effect of the device, and keeping a constant supply of water in the basin A. The piston D is represented as being provided with spiral flanges b , whereby the water in the cylinder C is pressed downwards, towards the bottom of the cylinder, as soon as the stem d is revolved. The stem d is tubular, and surrounds a tube, e , which is secured to the bottom of the basin and cylinder, and which tube e is of sufficient height to prevent the water from flowing into its upper end and down to the driving machinery. A vertical shaft, f , passes through the tube e , and its upper end is coupled with the upper end of the stem d , so that, as the shaft f receives motion from a spring, g , it revolves the stem d , and thus operates the piston in the desired manner. The spring g is secured to one of the standards B, and can be easily wound up in the usual manner, and operates a series of gear-wheels, through which the motion is increased, so that the shaft f revolves rapidly. H is a musical box, which may be arranged below the basin A, and which may be easily operated by the action of the spring g .

The cylinder C may be arranged so as to form a depression in the bottom of the basin A, and any desired number of pumps and jets may be arranged to one basin, A, as may be found desirable.

Having thus described my invention, what I claim as new, and desire to secure by Letters Patent, is—

1. The combination and arrangement, upon the pediment B, of the basin A, to the bottom of which is secured the metal ring C, with the perforated basin F, through which the tube E passes, flanged piston D, within the ring C, and music-box H, as described, all operated by the clock-work, substantially as herein set forth, for the purpose specified.

2. The tube e , as arranged around the shaft f and in the stem d of the revolving piston D, in combination with the cylinder C, secured to the bottom of the basin A, so that no joints are in the device that would require packing to keep them water-tight, as set forth.
